UNITED STATES PATENT OFFICE

NATHAN R. WATERS, OF ST. LOUIS, MISSOURI, ASSIGNOR TO WATERS & WATERS MANUFACTURING COMPANY, OF ST. LOUIS, MISSOURI, A CORPORATION OF MISSOURI

PEN AND INK STAND

Application filed April 23, 1926. Serial No. 104,067.

My invention relates to devices of the class described adapted to be used on desks, and consists in an improved structure adapted to facilitate the use of an ordinary pen or a fountain pen, or both.

It is an object of my invention to provide a pen and ink well in which the ink well will be protected at all times from the air which tends to evaporate the moisture from the ink and produce deposits of the ink solids which are unsightly and are picked up by the pen and interfere with the use of the same. The cover also protects the ink from the accumulation of dust in the ink.

It is desired that the protecting means thus afforded for the ink be of such nature that it is unnecessary to remove a cover every time the pen is to be dipped into the ink, and the elimination of this inconvenience is a further object of my invention.

Another object of my invention is to support a pen-holder in such a manner that the point is always immersed in the ink when not in use, thereby avoiding the corrosion of the pen point due to the drying of the ink thereon.

I also desire to provide a structure of the class described which is easily manufactured, is easily assembled, and is easily cleaned when necessary.

In attaining these general objects, various detail objects arise, and these will be referred to in the following description.

In the accompanying drawings which illustrate a preferred embodiment of my invention,

Figure 1 is a top view of my improved structure.

Figure 2 is a horizontal section through the device taken approximately on line 2-2 of Figure 3.

Figure 3 is a vertical transverse section taken on the line 3-3 of Figure 1.

Figure 4 is an enlarged detail in section of the pen seating features indicated in Figure 3.

The body of my device is shown as rectangular in shape, although this is not essential. One side of the body forms a reservoir 1. The opposite side of the device is pro-

vided with a pen filling inkwell 5 connected to the reservoir by a passageway 7. The well 5 is much smaller in volume than the reservoir 1 and may be repeatedly refilled by tilting the inkstand. After each tilting, the surplus ink will run back into the reservoir and the height of the ink level in the well 5 will never remain above the ridge 9.

The top wall of the inkstand is provided with a large opening over the inkwell, and a removable cover 10 fits into this opening and is preferably detachably secured in place by having lugs 12 adapted to project laterally under the top wall 13 of the stand. The edge of the opening in the top wall has suitable recesses 14 adapted to permit the insertion of lugs 12, and I also desire to provide a gasket 15 between the lower face of wall 13 and the lugs. The object of the gasket is to permit the use of glass containers and glass or other rigid covers, which, because of the gasket, will be able to expand and contract without cracking. The body portion of the inkstand is recessed at 16^a to accommodate lugs 12.

That portion of the upper face of cover 10 which immediately surrounds the central opening in the cover is substantially horizontal, and in combination with this cover and the well below the same I provide a novel pen holder 17 in which the finger grip portion 18 has its lower end shouldered as more clearly detailed in Figure 4 so as to provide a short portion 19 of relatively small diameter adapted to closely fit into the opening in cover 10. The periphery 20 of the shoulder is projected downwardly somewhat by making the shoulder concave, and this construction affords supporting points for the pen holder spaced substantially from its axis. The combination of the frictional engagement of portion 19 with the cover 10 and the wide bearing afforded by the shoulder insures a stable support for the pen holder in vertical position with the pen point 21 immersed in the ink in the well.

I am aware that it has been suggested heretofore to provide pen-holding inkwells in which the pen holder is thrust into a rubber cork-like element which contacts with the

finger grip portion of the pen holder throughout a substantial area. Such devices, however, result in smearing the finger grip portion of the pen holder with ink which is transferred from the pen point to the pen holder engaging portion of the cover.

With my device, the only portion of the pen holder which contacts with the cover is below the area engaged by the fingers of the user and the vertical surface of the opening in the cover is so short that it is easy for the pen point to be inserted in the opening and removed therefrom without contacting with the cover. Even if such contact is made, the area is so small that no substantial accumulation of ink will follow and, as previously stated, no ink will be transferred to the finger grip portion 18.

Obviously the details of my invention may be changed substantially without departing from the spirit of my invention, and I contemplate all such modifications as fall within the scope of my claim.

I claim:

25 In combination, an ink stand including a dipping well, a horizontal member extending over said well and provided with a restricted opening, and a pen holder with a portion having a finger gripping surface, said holder terminating adjacent to said portion in an inwardly offset projection spaced from said surface, snugly fitting in said opening and being barely long enough to engage the sides of said opening, the shoulder formed by 30 said projection and portion resting on top of said member, whereby said pen holder closes said well and is stably supported in upright position.

35 In testimony whereof I hereunto affix my signature this 19th day of April, 1926.

40 NATHAN R. WATERS.
